Primary Examiner—Ralf Seifert(74) *Attorney, Agent, or Firm*—Baker Botts L.L.P.**CLAIM**

The ornamental design of a gemstone arrangement, as shown and described.

DESCRIPTION

FIG. 1 is a front elevational view of a gemstone arrangement showing my new design.

The broken lines are provided for illustrative purposes only and form no part of the claimed design. In addition, the portions of the gemstone arrangement that are not shown in the drawing do not form any part of the claimed design.
